UNITED STATES PATENT OFFICE.

JAMES REED, OF NEWVILLE, OHIO.

WATER-WHEEL.

Specification of Letters Patent No. 31,739, dated March 19, 1861.

To all whom it may concern:

Be it known that I, JAMES REED, of Newville, in Richland county and State of Ohio, have invented certain new and useful Improvements in Water-Wheels; and I do hereby declare that the following is a true, full, and exact description of the same, reference being had to the accompanying drawings, which are a part of this specification.

10 Figure 1 is a sectional view of a hub of a water wheel, having buckets like those used in my improvements. Fig. 2 is a top or plan view of a wheel having such buckets. Fig. 3 is a view in perspective of one of my 15 improved water wheels, in connection with a chamber, into which the water that moves the wheel passes. Fig. 4 is a sectional view of a cross section of one of the buckets of my improved wheel, showing the convexity 20 of its upper surface.

To remedy the deficiencies I have observed in the water wheels now in use, I have ascertained, from actual experiment, that water wheels to be most efficient, should be constructed so as to receive the power of the water when applied agreeably to its most efficient law, upon a surface of such a character as to receive the greatest effect from it, when thus applied.

30 My invention consists in the construction, and application of an eccentrically spiral and convex bucket, to the hub, or shaft of the wheel, said shaft having a vertical, or nearly vertical position, in order that the 35 buckets may receive the full power of the water when applied agreeably to its most efficient law.

The bucket used in my improvement descends spirally, from its upper terminus, in 40 nearly the same degree for about three fifths of its length, whence it descends, spirally, much more rapidly to the point at which the water issues from the wheel. I contemplate using only two such buckets on 45 my improved wheel, and their respective ends fail to meet, on the hub, or shaft of the wheel, by the space of an inch, more or less. I place a band around the periphery of this wheel, of the width of the space, or 50 width on the hub thereof, covered by the buckets. I apply the water to my wheel according to the hydrostatic rule, or principle of its action, by conveying it, through a proper or convenient conduit, into a chamber, of the exterior shape, and annexed to

the band, or rim of the wheel, and of any convenient height. Said chamber may extend above the point, on it, at which the water is let into it, and the hydrostatic pressure, therefore will be greater or less as 60 the water is high or low in the chamber, or if the chamber be only of a fixed height, the power will be greater or less as the elevation of the water above the chamber, is greater or less in the flume or reservoir from which 65 it is conducted to the chamber.

As the principle of the power of the pressure of water, when hydrostatically applied is well settled as a scientific fact, any remark upon it will not be needful in this specification. It will be remarked, however, that it 70 has been shown, by experiment, that my wheel, on a trial in comparison with other wheels of the character set forth in my disclaimer was more efficient under equal 75 circumstances.

The letter A, Fig. 1, represents the character, shape, and position, on the shaft, or hub of the wheel, of the bucket in my improved water wheel, which in its downward 80 inclination, is spiral to a certain degree for about three-fifths of its length, whence it descends, spirally, more rapidly to its end at which the water flows from the wheel. The ends of the buckets are brought to an 85 edge, or nearly so, and the lower side of the bucket is of a smooth surface, and nearly conforms in shape to the upper side. I have constructed my bucket of this form, for the purpose of securing the power of 90 the hydrostatic pressure upon the whole surface of the bucket; and at the same time have provided by the more rapid descent of the lower part of the bucket, to receive the side pressure of the water against the 95 bucket, in the line of its motion.

The letter B, represents a chamber, drawn in red ink, for the reception of a column of water by the hydrostatic pressure of which my wheel is to be moved, and which may be 100 carried to any convenient height. It is to be of the exterior shape, and diameter of my wheel, and is to be placed on or over it in such a manner as will permit a free revolution of the wheel, which is represented in 105 black ink, as on its shaft, or spindle, and standing on the block, in red ink, marked D, Fig. 3.

I am aware that water wheels, with buckets spiral and concave and plano spiral have 110

been used before the date of my application; and I therefore disclaim each and all of them; but

What I claim as new, and of my invention is,

1. A plano convex spiral bucket, for water wheels, as set forth, and substantially as described.

2. A bucket for water wheels, of the char-

acter above stated, in combination with a circular chamber for the purpose set forth and substantially as described.

In testimony of which invention, I hereunto set my hand.

JAMES REED.
